UNITED STATES PATENT OFFICE.

ALFRED BERSTED AND MARTIN BERSTED, OF CHICAGO, ILLINOIS.

DESIGN FOR A WAFFLE IRON OR SIMILAR ARTICLE.

Application filed November 28, 1924. Serial No. 11,524. Term of patent 14 years.

To all whom it may concern:

Be it known that we, ALFRED BERSTED and MARTIN BERSTED, both citizens of the United States, and residents of the city of Chicago, in the county of Cook and State of Illinois, have invented a new, original, and ornamental Design for a Waffle Iron or Similar Article, of which the following is the specification, reference being had to the accompanying drawing, forming a part thereof.

On the drawings:

Figure 1 is a side elevation of a waffle iron showing our new design.

Figure 2 is a similar view taken at a right angle to Figure 1.

We claim:

The ornamental design for a waffle iron or similar article, as shown.

ALFRED BERSTED.
MARTIN BERSTED.
